FILLING MACHINE

Frederick E. Fauth, Baltimore, and Daniel J. Bustraan, Lutherville, Md., assignors to Crown Cork & Seal Company, Inc., Philadelphia, Pa., a corporation of New York

Filed July 15, 1959, Ser. No. 827,246

18 Claims. (Cl. 141—149)

The present invention relates to a filling machine, and more particularly, to a rotary filling machine having an improved container supporting platform mechanism which is adapted to receive containers and move them into engagement with filling heads for filling while the containers are moving in a circular path and further an improved arrangement for supporting the rotary turret structure on the stationary frame structure.

Filling machines of the type disclosed herein generally include a stationary frame structure having a work table thereon for receiving containers transferred thereto by flat top endless type of conveyors. The stationary frame structure supports a rotary turret structure which includes the reservoir for the liquid, filling heads operatively carried by the turret and communicating with the reservoir and a plurality of container supporting platforms, one platform being in vertical alignment and beneath each of the filling heads. The container supporting platforms are adapted to receive containers as they are transferred from the flat top conveyor by suitable infeed dials, the platforms then being moved vertically upwardly to a position where the container makes sealing engagement with the filling head thereabove.

After the container has sealing engagement with the filling head and while the rotary structure is rotating, the container is usually first placed under counterpressure and then filled with liquid from the reservoir. In some instances, there is a "sniffting stage" in the filling cycle so that the container can be lowered away from the filling head without foaming. This is usually done when the beverage is a carbonated soft drink. On the other hand, it is not usually necessary to sniff when the beverage is beer or ale. The container is lowered away from the filling head by the lowering of the platform immediately after the filling cycle is complete and it is then transferred off of the rotary turret structure by an out-feed dial. The containers are then transferred to a crowner or other equipment for closing the same.

According to the United States Patent No. 2,824,584, issued February 25, 1958, on an application of Rudolph H. Breeback, each container supporting platform mechanism includes a piston and cylinder arrangement whereby a first fluid pressure is applied to raise the container supporting platform with a container thereon to an elevation where the container is in sealing engagement with the filling head. Then a second fluid pressure, at a higher predetermined value, is applied to the cylinder so that the container is held in tight sealing engagement with the filling head. After the container had been filled, and the container supporting platform had moved to a position where it engages a pull down cam, the platform was positively moved to its lower position by the pull down cam and the fluid pressure in the cylinder either released just prior to, during, or after the lowering of the platform depending on the operating condition of the particular filler.

An object of the present invention is to provide an improved container supporting mechanism for filling ma-

2

chines wherein the container supporting platform is raised from a lower position to a higher position by the use of fluid pressure.

In prior filling machines of the type disclosed in the 5 aforementioned Breeback patent, the rotary turret structure, which included a rotary filling table and a superposed reservoir was mounted on a central column journaled in the stationary frame structure or work table by a thrust bearing. Since the rotary table extended outwardly from the central column a considerable distance and was quite heavy and since the liquid reservoir and the filling heads extended outwardly of the central column, tremendous forces were exerted on the thrust bearing.

10 An object of the present invention is to provide a filling machine of the rotary type with a bearing arrangement which increases the stability of the filling machine at high r.p.m. by more evenly distributing weight of the rotary turret structure over the stationary frame structure.

15 Another object of the present invention is to provide a rotary filling machine with a hydrostatic bearing arrangement whereby the rotary turret structure is effectively supported on the stationary frame by a film 20 of lubricating liquid such as oil or the like. Such an arrangement provides less friction between the moving parts and a greater mass can be rotated at higher speeds with less vibration being set up during the filling cycle from other moving parts such as the vertically moving 25 container supporting platforms, engagement of the filling 30 valves of the filling heads with stationary cams, and the like.

35 A still further object of the present invention is to provide a filling machine with novel means of controlling fluid pressure to the cylinders of the container lift platforms whereby the platforms can be reciprocated vertically while the rotary structure of the filling machine is moving.

40 Another object of the present invention is to provide a rotary filling machine having a container supporting platform movable vertically and utilizing differential pressures acting on the platforms during elevation of the container supporting platform whereby containers can be placed into tight sealing engagement with the filling 45 heads without causing a jarring action to the filling machine.

50 Still another object of the present invention is to provide a filling machine having a lift mechanism for the container supporting platforms utilizing fluid pressure to raise the platforms and utilizing gravity to lower the platforms.

55 A still further object of the present invention is to provide a rotary filling machine having container supporting platforms raised by fluid pressure and lowered by gravity, the cylinders of the platforms being provided with means to snub or cushion the downward movement of the platform so that there is no jarring action on the filling machine during the operation of the lift platforms.

60 Further, an object of the present invention is to provide a rotary filling machine utilizing a hydrostatic bearing for supporting the entire rotary turret structure and evenly distributing the weight of the rotary turret structure over the stationary frame structure, the hydrostatic bearing being utilized to provide a manifold or air distributor valve for the fluid pressure used in operating the individual cylinders of the lift platforms.

65 Ancillary to the preceding object, it is an object of the present invention to provide an air manifold or distributor valve in the hydrostatic bearing whereby the lubricating liquid of the hydrostatic bearing provides an effective baffle or seal for the air pressure.

70 A further object of the present invention is to provide

a filling machine having a rotary turret structure and a stationary frame structure utilizing an annular hydrostatic thrust bearing, the rotary turret structure being effectively supported on the stationary frame structure by a thin film of liquid at a predetermined pressure, means being provided to stop rotation of the rotary structure upon dropping of the pressure below a predetermined value.

These and other objects and advantages of the present invention will appear more fully in the following specification, claims and drawings wherein:

Figure 1 is a side elevational view of the filling machine of the present invention provided with improved lifting mechanism for the container supporting platforms and with an improved means of mounting the rotary turret structure on the stationary frame;

Figure 20 is a schematic flow diagram for the bearing lubricating fluid of the filling machine of the present invention.

Referring now to the drawings wherein like character or reference numerals represent like or similar parts, the filling machine of the present invention is illustrated in general assembly in Figure 1 and includes a stationary frame structure generally designated by the numeral 10, and a rotary turret structure generally designated by the numeral 12 supported for rotation upon the stationary frame structure. The stationary frame structure 10 is provided with a base casting 14 supported on standards 16 and having a lower floor 18 and an upper horizontal table surface 20. Mounted to one side of the rotary

turret structure 12 and forming part of the stationary frame structure 10 is a work table 22 having a container supporting surface 24 and across which runs a conventional flat top type of endless chain conveyor 26. Also mounted on the work table 22 is an article spacing and timing screw 28 which has its axis parallel to and spaced from the axis of the conveyor 26. The feed screw 28 engages containers traveling on the conveyor 26 and properly spaces and times the containers so that they may be received in the pockets of a rotary infeed dial 30 also mounted on the work table 22.

Rotary turret structure 12 includes a cylindrically shaped body member 32 which carries adjacent its lower end a plurality of container supporting platform mechanisms 34. A donut shaped reservoir 36 is carried on the upper end of the cylindrically shaped body member 32, the donut shaped reservoir being provided with a plurality of filling heads 38, each filling head having a valve operating arm 40. Details of the filling head 38, its filling valve and valve operating arm are disclosed and claimed in the copending application of Carl L. Day et al. Serial Number 542,811, filed October 26, 1955, entitled "Filling Head" and now United States Patent No. 2,876,674 issued July 28, 1959. In the aforementioned Day et al. application, the filling head disclosed and claimed is particularly adapted for filling machines of the type filling containers with carbonated liquids such as soft drinks, soda water or the like. While the present invention is shown in association with a filling machine for filling containers with a carbonated liquid, it will be understood and within the scope of the present invention to use filling machines having other types of filling heads and for filling other types of liquids.

The details of the filling head and its operation is not disclosed specifically herein but is disclosed in the aforementioned copending application of Day et al and to that extent forms a part of the present disclosure. It will suffice to say that containers traveling on the endless conveyor 26 are spaced by the timing and spacing screw 28 so that they can be received in the pockets of the infeed spider 30 which in turn transfers them onto the container supporting platform mechanisms 34. The platform mechanisms 34 are raised vertically until the container engages the filling head 38 immediately thereabove in a tight sealing relationship. The rotary turret structure 12 is continuously moving on a vertical axis and the valve operating arm 40 of the filling heads 38 are moved to various positions by engagement with a stationary cam (not shown). A typical filling cycle is to first place the container under counterpressure, then fill the container with liquid from the reservoir and finally snift pressure from the container prior to the container being lowered away from the filling head 38. After the containers are lowered, they are taken off of the platforms by a take off spider (not shown) and are transferred to suitable mechanism for closing the same such as crowners if the container is a bottle or can end seamers if the container is a can.

The reservoir 36 is filled to a desired level with carbonated liquid from a suitable source (not shown) by a pipe 42 extending from the source to a suitable swivel connection or fitting 44 as shown in broken lines in Figure 1 and from the swivel connection through a pipe 46 branching into the reservoir as indicated at 48. The swivel connection or fitting 44 also provides a radial bearing between the stationary frame structure 10 and the rotary turret 12. Counterpressure gas such as carbon dioxide is fed through the pipes 50 from a suitable source (not shown) to a swivel head or fitting 52 where it in turn feeds the gas to the area of the reservoir above the liquid by the branch conduits 54 shown in dotted lines in Figure 1. Suitable means will be provided to control the level of liquid in the reservoir 36 as well as the pressure of the superposed gas. A gage 56 is mounted on the reservoir

36 to indicate the pressure of the gas on the liquid therein.

Referring now to Figure 2, the stationary frame structure 10 is provided on its upper horizontal table surface 20 with an annular bearing ring 60. The annular bearing ring 60, which is shown in a top plan view in Figure 3 and which has a diameter substantially equal to the diameter of the rotary turret structure, is provided with a plurality of holes 62 on its bottom surface (Figure 11) which are adapted to receive, by a press fit, pins 61 extending upwardly from the horizontal table surface 20. The pins 61 anchor the ring 60 to the horizontal table surface 20. A suitable annular gasket 64 may be inserted between the ring 60 and the horizontal table surface 20 so that it makes a fluid tight seal therewith.

Welded to the lower end of the body 32 of the rotary turret structure 12 as shown at 66 is an annular flange or ring 68. Flange 68 is provided with a plurality of circumferentially spaced holes 70 about its inner periphery. A ring gear 72 is bolted to the flange 68 by studs 74 extending through the holes 70 and threaded into the ring gear. Ring gear 72 is adapted to mesh with a drive gear 76 mounted on a shaft 78 as shown in Figure 17. The shaft 78 is journaled in a suitable bearing 80 shown in broken lines in Figure 1, the bearing 80 being mounted on the floor 18 of the stationary frame structure 10. Shaft 78 extends upwardly through a bearing 82 carried in the horizontal table 20. Also mounted on the shaft 78 is a gear 84 which is driven by a suitable chain drive or like 86 from a speed reduction unit 88. Speed reduction unit 88 is coupled through a belt 89 to a suitable source of power such as the electric motor 90. As is now evident, when the motor 90 is energized, it will drive the rotary table through the speed reduction unit 88, chain drive 86, gear 84, shaft 78, and gear 76.

Also mounted on the lower end of the cylindrically shaped body 32 of rotary turret structure 12 is a bearing ring 92 having a downwardly facing horizontal bearing surface 94 adapted to cooperate with an upwardly facing horizontal bearing surface 96 of the annular bearing ring 60. In more detail, annular bearing ring 92 is provided with a cutout portion 98 on its inner periphery, the cutout portion 98 being adapted to receive the outer peripheral portion of flange 68. Suitable clamping members generally indicated at 100 are provided to clamp the bearing 92 to the body member 32 of rotary turret structure 12. The clamping members 100 include a L-shaped element 102 adapted to have one end fit through an aperture or hole 104 in the body member 32. The other end of the L-shaped members 102 is adapted to bear against the upper surface of bearing ring 92 as indicated at 106. A stud 108 extending through the L-shaped member 102 and threaded into the annular bearing ring 92 is adapted to draw the ring into tight engagement with the flange 68 and the L-shaped member 102.

Welded to the outside periphery of the cylindrically shaped body member 32 as indicated at 110 is an annular flange 112 having a cutout portion 114 adjacent its outer end. The flange 112, which is spaced upwardly of the bearing ring 92, may be provided with a plurality of holes 116 which make the unit lighter and also provides an area for any liquid spilled by a container to drain. Each of the container supporting platform mechanisms 34 include a cylinder 118 closed at its upper end by a fitting 120 and at its lower end by a second fitting 122. The fitting 120 is provided with an ear 124 which is adapted to receive a plurality of studs 126 therethrough so as to bolt the upper end of the cylinder 118 to the flange 112. As shown in Figure 19, the fitting 122 on the lower end of the cylinder is adapted to be secured to the annular bearing ring 92 by means of studs 126. Suitable O-rings or gaskets 128 are provided between the surface of the fitting 122 and the peripheral edge of the bearing ring 92 so as to provide a tight seal with the same.

The fitting 120 is provided with an axial bore 130 there-

through and square in cross-section, which is adapted to receive the upper end of a piston rod 132 which is also square in cross-section. Mounted on the upper end of piston rod 132 is a platform 134 having a horizontal surface for receiving the container and suitable container centering means 135. A flexible shield 136 carried on the bottom of the platform 134 and extending downward and outwardly therefrom provides an effective guard to prevent liquid or dirt entering the area where the piston rod 132 extends from the end of the cylinder 118.

Mounted on the lower end of the piston rod 132 is a double acting piston 140 having an upwardly facing gasket 142 and a downwardly facing gasket 144. The piston 140 includes a lower head 146 and an upper head 148 threaded onto a tubular body 150. The head 146 is bolted to the lower end of the piston rod 132 by means of the stud 152, the stud having a lower axially extending projection or pin 154. The fitting 122 is provided with a passageway 156 which is in axial alignment with the piston 140 and which is a sufficient diameter to receive the projection or pin 154 on the piston 140 when the piston is in the lower position as shown in Figure 2 and still permit air under pressure to be applied beneath the piston. The passageway 156 is closed at its lower end but communicates with a transversely extending passage 158 which in turn communicates with a passage 160 in the bearing ring 92. The passage 160 extends radially of the bearing ring 92 and then extends downwardly and terminates in a port 162 as best shown in Figure 5.

As will now be understood, if a gaseous fluid under pressure, such as compressed air or the like, enters the port 162 to the passageway 160, it will act on the lower head 146 of piston 140 to cause the piston to move vertically upwardly in the cylinder 118. A hole 164 in the upper end of the cylinder 118 provides a means for escape to atmosphere of air above the piston. The size of the hole may be controlled to determine the speed at which the piston may be moved upwardly in the cylinder 118. Since the piston is fixedly connected to the piston rod 132, the piston will cause the rod 132 to extend upwardly through the fitting 120 to thereby raise the platform 134 and a container positioned thereon into the sealing engagement with a filling head 38. When the pressure of the air is released from beneath the piston 140, the weight of the container, the container supporting platform 134, piston rod 132, and piston 140 is sufficient to cause the unit to fall by gravity to the lower position as shown in Figure 2. In order that there will be no jarring action when the piston reaches a limit of its downward or exhaust stroke, the projection or pin 154 entering the restricted passage 156 will cause a cushioning of the down stroke and will effectively brake the downward travel of the piston.

A more detailed explanation of the application of fluid pressure to the piston 140 through the annular bearing rings 92 and 60 will follow later in the specification.

Referring now specifically to Figures 3 to 16 inclusive, it will be noted that the lower annular bearing ring 60 is provided on its upwardly facing horizontal surface 96 with an arcuate groove or manifold 170 which extends between a babbitt 172 and a second babbitt 173. As shown in Figure 4 and Figure 9, the annular bearing ring 60 is provided with a port 176 in which a pipe 178 (shown in broken lines, Figure 9) extends to a pressure regulator (not shown), carried in the base 14 of the frame structure 10. The pressure regulator is supplied with a gaseous fluid such as compressed air by a pipe 179 through filter 181, the pipe 179 extending to a suitable source of compressed air (not shown). At the far end of the groove 170 adjacent the babbitt 173, as shown in Figure 3 and Figure 16, a second port 180 is provided in the bearing ring 60 and is connected to a pipe 182 which leads to an oil reservoir or sump 184 (Figure 20) as will be explained in more detail later in the specifi-

tion. It will suffice to say that the air or gaseous fluid under pressure in the groove 170 is partially exhausted through the pipe 182 to atmosphere by passing it through the reservoir 184. The port 180, is, of course, of much less diameter than the port 176 so that a desired pressure of approximately 12 p.s.i. can be maintained in the groove or manifold 170 of the bearing ring 60.

Figure 13 which is a sectional view through the bearing ring 60 shows the babbitt 172 held in place at the end of the groove 170 by a pin 186. The babbitt 173 is mounted at the other end of the groove 170 in identical manner so that a cross section through the annular bearing ring 60 on the line 13'-13' of Figure 3 would be identical to the view shown in Figure 13.

A second arcuate groove or air manifold 188 extending from the babbitt 173 around the ring to a babbitt 190 provides a second manifold for the application of gaseous fluid to the cylinder 118 at a secondary pressure of approximately 20 p.s.i. The gaseous fluid enters the groove 188 through a port 192. It is partially exhausted from the groove through a small port 194. The cross section of the bearing ring 60 on the line 9'-9' of Figure 3 is identical to that shown in Figure 9 and therefore, is not repeated in the drawings. However, it will be understood that a pipe is connected to the port 192 and extends to the pressure regulator where it receives gaseous fluid from the source at a pressure higher than the pressure of gaseous fluid supplied to the groove 170. Likewise, a view through the bearing ring 60 on the line 16'-16' of Figure 3 is identical to the cross sectional view shown in Figure 16 and is not repeated in the drawings. However, in the schematic view of Figure 20 the pipe connected to the port 194 is indicated at 196 and leads therefrom to the reservoir 184 where the air is effectively exhausted therethrough to atmosphere.

An arcuate groove or exhaust air 198 extending between the babbitt 190 and the babbitt 172 provides a segment wherein the compressed air previously applied to the bottom of the piston 140 in cylinder 118 may be relieved to atmosphere so that the piston 140, piston rod 132, and container supporting platforms 134 can drop by gravity and lower a container away from the filling head 38 after the container has been filled. Groove 198 is positioned on ring 60 adjacent the infeed and outfeed stations of the filling machine so that the platforms will be in the lowered position when adjacent this area. Annular bearing ring 60 is provided with an arcuate elongated slot 200 which communicates with the bottom of groove 198. The slot 200 cooperates with a fitting 202 carried by the table 20, the fitting 202 being connected to a pipe 204 which leads to a T-connection 206. The branch 208 extending vertically upwardly from the T-connection will exhaust the air from beneath the piston directly to atmosphere whereas the other branch 210 of the T-connection 206 leads back to the oil reservoir of sump 184 where any oil entrained in the air supplied beneath the piston can drain and return to the sump. A second pipe 212 extending off of the line or pipe 210 vertically above the same permits filling the sump 184 after a lubrication drain.

As is now evident from the above description, the operation of the lift platform mechanism 34 is such that a primary pressure is applied to the lift piston 140 in order to elevate the same and the container supporting platform 134 to its uppermost position. After the primary air has been applied to the piston at a predetermined pressure of 12 p.s.i., then a secondary air is applied to the piston at a higher pressure of 20 p.s.i. so as to maintain the container on the container supporting platform 134 in tight sealing engagement with the filling head 38 thereabove during the filling cycle. The secondary air is maintained on the platform during the entire filling cycle and after the container has been filled, the air pressure on the piston 140 is released to atmosphere so the platform will drop by gravity to its

lower position. It will now be understood that when the rotary structure 10 rotates, each port 162 in the annular bearing ring 92 successively cooperates with the grooves 170, 188, and 198 to sequentially cause

5 the platform to raise, be held in the raised position at an increased pressure and then lowered. Effectively, the fluid pressure grooves 170, 188, and 198 in the ring 60 and the port 162 in the bearing ring 92 cooperating therewith as it is moved past the same, is a distributor 10 valve for controlling the operation of the lift platforms.

In order that the air supplied under pressure to the grooves 170, 188, and 198 cannot leak outwardly between the bearing surfaces 96 and 94 of the bearing rings 60 and 92 respectively, a film of oil under pressure is applied

15 to the bearing surfaces on either side of the grooves 170, 188, and 198, the oil providing an effective seal for the air as well as a lubricating liquid whereby the annular bearing ring 92 is supported on the stationary annular bearing ring 60 by a film of liquid. In other

20 words, the entire rotary structure 12 is supported on the stationary structure through the bearing rings 60 and 92, the thin film of lubricating liquid between the bearing rings providing a hydrostatic bearing for the assembly. Since the annular bearing rings 60 and 92

25 having a diameter substantially as great as the rotary turret structure 12, the weight of the rotary turret structure is more evenly distributed on the stationary frame structure and consequently, higher speeds of filling can be obtained by rotating the rotary structure at a faster

30 r.p.m. than heretofore known.

In order to provide a film of lubricating liquid such as oil between the bearing surfaces 96 and 94, of the bearings 60 and 92 respectively, the bearing surface 96 of stationary bearing ring 60 is provided with a first pair

35 of concentrically spaced oil grooves 214 radially outwardly of the air manifolds or grooves 170, 188, and 198 and a second pair of concentrically spaced oil grooves 216 radially inwardly of the air manifolds or grooves 170, 188, and 198. Between the pair of grooves

40 214 there is a concentric oil return groove 218 whereas between the pair of oil grooves 216 there is a concentric oil return groove 220. The oil grooves 214 and 216 are provided with babbitts 222 as best shown in Figure 3 and Figure 12. The babbitts 222 are held in position by

45 pins 224 in the same manner as the pin 186 holds the babbitt 172 in place. It will also be noted that the babbitt 190 is radially spaced with respect to the babbitts 222 and is held in place by a pin 226. The babbitts 222 provide an effective dam for the oil grooves and

50 their purpose will be explained in more detail later in the specification.

Referring now to Figure 20 which is a schematic flow diagram, oil or other lubricating liquid from sump 184 flows through a strainer 228 to a positive displacement

55 pump 230. The pump 230 is provided with a bypass 232 which has a back pressure relief valve 233. The oil is normally pumped through the line 234 to an oil filter 236. A pressure gage 237 provided on the oil filter 236 and suitably mounted on the machine gives

60 an indication of the pressure being developed by the pump 230. The oil from the filter 236 flows to a cross fitting 238 where it in turn flows in four separate lines 240, 242, 246, and 248 to the oil grooves 214 and 216 of the bearing ring 60. In more detail, the line 240

65 connects to the bearing ring 60 as shown in Figure 7 and on the line 7-7 of Figure 3 and communicates with a port 250. The port 250 connects with the passageway 252 which in turn communicates with the pair of grooves 214. The line 248 connects to a port 254 which in turn

70 connects to a passageway 256 that communicates with the pair of grooves 216 in the bearing 60. The lines 246 and 242 supply the grooves 214 and 216 respectively at a different location on the bearing ring 60 in exactly the same manner as the lines 240 and 248 as shown in Figure 7. In other words, the line 242 and

248 communicate with the ports 258 and 260 as shown on the section line 7'-7' of Figure 3.

Oil under pressure in the grooves 214 and 216 tend to flow clockwise in the grooves as viewed in Figure 3 since the bearing ring 92 is rotating in a clockwise direction. Adjacent the dams or babbitts 222, a pair of outlet ports 262 and 264 are provided to communicate with the grooves 214 and 216 in the identical manner as shown in the sectional view of Figure 7. Lines 266 and 268 communicating with the ports 262 and 264 lead to a cross fitting 270, one branch 272 of the cross fitting extending to a back pressure valve 274 and to a pipe 276 which extends through the table 20 of the stationary frame structure and empties onto the ring gear 72 and drive gear 76 so as to lubricate the same. The other branch 278 of fitting 270 extends to a pressure gage 280 and to a pressure responsive switch 282 in the electrical circuit 284 for motor 90. So long as there is sufficient pressure in the grooves 214 and 216 the pressure responsive switch 282 is held in the closed position and the motor 90 can operate. If for any reason the pressure in the grooves 214 and 216 drops below a predetermined value the switch 282 opens breaking the circuit to the motor 90 thereby stopping the same so that the rotary turret structure stops and the bearing is not damaged. This arrangement provides a means to prevent the bearing rings 60 and 92 from rotating relative to one another unless there is sufficient pressure between the horizontal surface 96 and 94 respectively to provide a thin film of liquid so that the bearing ring 92 is supported thereby on the bearing ring 60.

When oil is being supplied to the grooves 214 and 216, it will flow in the direction of the arrows shown in Figure 6. A certain amount of the oil will pass radially outwardly and inwardly of the bearing ring 60 whereas a certain amount of the oil will flow into the oil return grooves 218 and 220 as well as into the air manifolds or grooves 170, 188, and 198. In order that the oil may be reclaimed and used over, the bearing ring 60 is provided with a plurality of radially extending slots 286 as shown in Figures 8 and 8a. The slots 286 communicate with the grooves 218 and 220 by means of vertical passages 288 and 290. As will now be evident, any oil flowing over the outer wall of the bearing ring 60 from the outermost oil groove 214 can flow radially inwardly along the table 20 of the stationary frame structure 10 through the slots 286. Also, the oil flowing into the return grooves 218 and 220 can flow into the slots 286 and then inwardly along the table 20 of the stationary frame structure 10. The oil flowing over the inner edge of the bearing ring 60 flows directly onto the table 20 of the stationary frame structure 10. In addition to the radially extending slots 286 which communicate with the return grooves 218 and 220, other radially extending slots 292 may be provided in the bottom surface of the bearing ring 60 as shown in Figures 14 and 15, the slots 292 assisting in transferring oil flowing over the outside of the ring 60 back toward the center and on the table 20. Table 20 is provided with the hole 294 which receives a fitting 296 having a downwardly extending pipe 298. The lower end of the pipe 298 is received in the reservoir or sump 184 so that oil flowing across the table top 20 can be returned directly to the oil reservoir. A breather 302 is provided on the reservoir 184 so that any air entrapped in the oil can escape from the reservoir to atmosphere.

In order that the oil escaping radially outwardly of the bearing ring 60 is not flung outwardly of the machine by the centrifugal force exerted thereon by the rotation of the rotary turret structure 12, an annular guard member 304 which is U-shaped in cross section is provided radially outwardly of the bearing ring 60. The guard member 304 is bolted to the table 220 by suitable studs 306. The upwardly extending legs 308 of U-shaped guard member 304 are received in a pair of spaced apart concentric annular grooves 310 provided in the downwardly

facing surface 94 of the upper bearing ring 92. The oil escaping from between the bearing surfaces 94 and 96 of the rings 92 and 60 will engage the inner leg 308 of the baffle or guard member 304 and will roll downwardly of the same and back through the slots 286 and 292 in the bottom of the ring 60. In addition to providing a guard against the oil or lubricating liquid from escaping outwardly, the guard member 304 effectively prevents any water from getting on the bearing rings 60 and 92 and more particularly, to the bearing surfaces and oil. As is customary in bottling plants, the filling machines are hosed down at the end of a day's operation or when they are changing from one flavored beverage to another flavored beverage. The guard member 304 provides an effective trap for the water and should the water get by the outermost leg 308 of the guard member 304, the water can drain outwardly of the machine through holes 312.

Operation

The operation of the filling machine may be briefly described as follows:

The reservoir 36 is suitably filled by liquid to be dispensed from a source not shown through the pipe 42. The superposed gas for the reservoir 36 is delivered through the line 50 from a suitable source of carbon dioxide. Assuming that the reservoir is filled with liquid to a predetermined level and under a predetermined pressure as determined by the CO₂ gas, the filling machine is ready for operation. Before the rotary turret structure 12 is started, the oil pump 230 is started so that oil may be pumped from the sump 184 through the line 234 to an oil filter 236 where it is then distributed to the oil grooves 214 and 216. Once the oil pressure has been built up in the grooves 214 and 216, such pressure will be reflected on the pressure gage 280 and the pressure switch 282 will be closed. When the pressure switch 282 is closed, the motor 90 can then be started. Simultaneously with the starting of the motor 90, a compressor (not shown) which supplies compressed air to the lift platforms 34 may be also started. With the starting of the motor 90, the rotary turret structure 12 begins to rotate with respect to the stationary frame structure 10.

Containers traveling on the straight line flat top conveyors 26 are picked up by the article feed and timing screw 28 and are delivered successively to the rotating infeed dial 30. The dial 30 transfers the containers onto the platforms 134 when the platforms are in their lowered position. Immediately after a container is received on a moving platform 134, the cylinder 118 carrying the platform will be moved with the turret structure 12 to a position where the bearing ring 92 moves the port 162 over the babbitt 172 and in communication with low pressure air manifold or groove 170. Compressed air at approximately 12 pounds p.s.i. is applied through the port 162, passageway 160 to the area beneath the piston head 146 of piston 140 to thereby raise the piston 140 vertically upwardly in the cylinder 118. The air above the piston head 148 is exhausted through the hole 164 to atmosphere. When the container supported on the platform 134 has been elevated to a position where it is in engagement with the filling head 38, the ring 92 will be moved to a position where the port 162 has passed the babbitt 173 and is in communication with the high pressure air manifold or groove 188. Compressed air is then applied beneath the piston 140 at approximately 20 pounds p.s.i. By applying the higher pressure to the lift platform mechanism 34 when it is in its upper position, the container makes a tight sealing engagement with the filling head 38 without a jarring action on the filling machine. As the ring 92 is rotating with the port 162 in communication with the elongated arcuate groove or air manifold 188 in ring 60, the filling cycle including application of counterpressure to the container, filling, and snifting, if desired, occurs. When the ring 92 is

moved to a position where the port 162 passes the babbitt 262, the compressed air under the piston 140 is exhausted through the port 200 in the exhaust manifold 198.

Since there may be some oil entrained with the air being exhausted through the exhaust manifold or groove 98, the port 200 is connected to the fitting 202 where the air and entrained oil is led to a passageway 204 to the standpipe 208. The air will be exhausted upwardly through the standpipe 208 to atmosphere while oil will drop downwardly into pipe 210 and to the sump 184.

As previously mentioned, the oil film provided between the bearing surfaces 94 and 96 of the bearing rings 92 and 60, respectively, serves two functions. First the oil film provides a hydrostatic bearing for supporting the turret structure 12 on the stationary frame structure 10. Second the oil film provides a means for sealing the area between the bearing surface on either side of the air manifolds 170, 188 and 198. In this respect, the oil pressure applied through the oil grooves 214 and 216 should be at least equal to or greater than the pressure of the air in the secondary air groove 188. In other words, if the air pressure in the groove 188 is substantially equal to 20 pounds p.s.i., the oil pressure in the grooves 214 and 216 as well as between the surfaces of the bearing rings 60 and 92 must be at least 20 pounds p.s.i. or greater.

At the end of each of the grooves 214 and 216, the ports 262 and 264 are provided for returning the oil to the sump 184. However, before returning the oil to the reservoir or sump 184, the oil passes through a back pressure valve 274 which maintains the necessary pressure in the grooves 214 and 216. The oil is flowed from the back pressure valve through a pipe 276 extending upwardly through the table 20 of the stationary frame structure 10. The pipe 276 is adapted to discharge the oil over the ring gear 72 and drive gear 76, the oil then dropping back onto the table 20 and through the aperture 294 and pipe 295 to the sump 184. The oil under pressure prior to going into the back pressure valve 274 is also fed to a pressure gage 280 through the ring 278 so that the operator of the machine may determine at what pressure the machine is operating. In addition, the oil actuates and closes the pressure operating switch 282 in the circuit 284 of the motor 90. Should the pressure of the oil in the groove 214 and 216 drop below a predetermined safe value, then the pressure operated switch 282 will open and the motor 90 will stop so that there can be no damage to the bearing surfaces 96 and 94 of the bearing rings 60 and 92 respectively. Oil which is not delivered directly to pipes 266, 268 but which flows outwardly and inwardly of the grooves 214 and 216 between the surfaces 94 and 96 is conveyed from the ring 60 to the table top 20 where it then returns through the hole 294, pipe 295 to the sump 184.

Any oil entrained in the air being exhausted from the grooves 170 and 188 is returned to the sump through lines 182 and 196 directly as the sump is also used as an exhaust means through which the air from the grooves 170 and 188 will exhaust to atmosphere.

A suitable sight gage 324 positioned at a convenient spot is connected by pipe 322 to the reservoir or sump 184. Petcock 320 is provided for draining of the sump 184 when it is desired to renew the oil.

Having set forth the nature, objects and advantages of the present invention, it will now be perceived that the container filling machine and more particularly, the arrangement for maintaining the rotary turret structure on the stationary frame structure as well as the novel means of providing a fluid pressure operated lift mechanism through the novel bearing arrangement provides for an improved filling machine capable of operating at extremely fast speeds with vibration due to rotation and actuation of various parts reduced to a minimum.

While the filling machine of the present invention has been described in its preferred embodiment, it is now

obvious that certain changes, adjustments and modifications could be made without departing from the principle and spirit of the invention. For this reason, the terminology used in the specification is for the purpose of description and not limitation, the scope of the invention being indicated in the claims.

We claim:

1. In a filling machine for filling containers: a stationary frame structure having an upwardly facing annular bearing surface, said surface being provided with at least a pair of concentrically spaced grooves having a lubricating liquid from a source of liquid supplied thereto at a predetermined pressure; a rotary turret structure having a downwardly facing horizontal annular bearing surface complimentary in size and cooperating with said upwardly facing bearing surface of said stationary frame structure, said rotary turret structure including a cylinder, a container supporting platform carried by said cylinder and operable from a lower position to an upper position by fluid pressure in said cylinder, a filling head positioned above and in alignment with said container supporting platform and a liquid reservoir; means for applying a fluid under a predetermined pressure through said bearing surfaces intermediate said grooves to said cylinder to cause container supporting platform to raise; means for returning lubricating liquid to said source from between said bearing surfaces; and means for exhausting fluid under pressure in said cylinder through said bearing surfaces intermediate said grooves to thereby lower said container supporting platform from its upper position.

2. A filling machine of the character described in claim 1 including means to stop said rotary turret structure when pressure of lubricating liquid between said first and second mentioned bearing surfaces drops below said predetermined value.

3. A filling machine of the character described in claim 1 wherein said means for returning lubricating liquid to said source includes pressure responsive means to stop said rotary turret structure when pressure of lubricating liquid between said first and second mentioned bearing surfaces drops below a predetermined value.

4. A filling machine of the character described in claim 1 including means communicating with at least one of said lubricating grooves and applying a back pressure to the lubricating liquid therein, said last mentioned means returning said lubricating fluid from said groove to said source.

5. A filling machine of the character described in claim 1 including means for returning lubricating liquid escaping from between said bearing surfaces to said source.

6. A filling machine of the character described in claim 1 including means to apply fluid pressure to said cylinder through said bearing surface intermediate said grooves at a predetermined pressure higher than said first mentioned predetermined fluid pressure for causing said container supporting platform to raise, said second mentioned fluid pressure being applied after said container supporting platform has moved to its upper position and prior to the exhausting of fluid pressure from said cylinder.

7. A filling machine of the character described in claim 1 wherein said fluid pressure applied to said cylinder is no greater than the pressure of the lubricating liquid applied to said grooves.

8. In a filling machine for filling containers: a stationary frame structure, said stationary frame structure being provided with an annular ring having a horizontal upwardly facing bearing surface; a rotary turret structure including a reservoir, a filling head carried on said reservoir, and container supporting means in alignment with and beneath said filling head, said rotary turret structure including an annular ring having a downwardly facing horizontal bearing surface complementary in size to and cooperating with the upwardly facing bearing surface of the ring on said stationary frame structure; said container supporting means including a cylinder carried by the ring

of said rotary turret structure; a piston in said cylinder and a container supporting platform carried by said piston and movable from a lower position to an upper position upon application of fluid pressure to said cylinder; means for applying a gaseous fluid under pressure to said cylinder through said first and second rings and means to provide a seal for said fluid pressure means between said bearing surfaces, said last mentioned means including means to supply a lubricating liquid under a pressure between said bearing surfaces substantially around the same and on each side of said gaseous fluid where said gaseous fluid passes through said first and second rings thereby providing a seal for said gaseous fluid as well as providing a film between said bearing surfaces for supporting said rotary turret structure for rotation on said stationary structure.

9. A filling machine of the character described in claim 8 wherein said piston is provided on its lower end with a short cylindrically shaped fitting and wherein said cylinder at its lower end is provided with a bore having a diameter substantially equal to said fitting and adapted to receive said fitting to cushion the downward stroke of said piston.

10. In a filling machine for filling containers with liquids: a stationary frame structure having a substantially horizontal table surface; an annular bearing ring fixed to and carried on said table, said bearing ring having a horizontal upwardly facing bearing surface, said bearing surface being provided with a first pair of concentrically spaced annular lubricating liquid grooves and a second pair of concentrically spaced annular lubricating liquid grooves, each pair of grooves extending substantially around said bearing surface, said surface also having a first arcuate gaseous fluid groove and a second arcuate gaseous fluid groove having a radius equal to the radius of the first arcuate gaseous fluid groove, said first and second arcuate gaseous fluid grooves being positioned on said surface between said first and second pairs of grooves; a rotary turret structure comprising a reservoir, a filling head carried on said reservoir and container supporting means in alignment with and beneath said filling head, said rotary turret structure including an annular bearing ring having a horizontal downwardly facing bearing surface cooperating with the upwardly facing bearing surface of the ring on said stationary frame structure; said container supporting means including a cylinder carried by the ring on said rotary turret structure, a piston in said cylinder and a container supporting platform carried by said piston; means for supplying a lubricating liquid under pressure from a source of lubricating liquid to each pair of said lubricating liquid grooves in said ring on said stationary frame structure; means for returning lubricating liquid to said source, said means including grooves in said upwardly facing bearing surface intermediate the grooves of each pair of grooves; means to supply a gaseous fluid under pressure to said first arcuate groove in the ring on said stationary frame structure; means providing communication at least to atmosphere from said second gaseous fluid groove in the ring on said stationary frame structure; and fluid connecting means between said cylinder and the horizontal downwardly facing bearing surface of said ring on said rotary turret structure, said last mentioned means being adapted to cooperate with said first and second gaseous fluid grooves to first raise the container supporting platform and then lower the container supporting platform.

11. A filling machine of the character described in claim 10 including a dam in each groove of each of said pair of grooves and means adjacent said dam providing communication between said pair of grooves and said source whereby lubricating liquid is returned to said source.

12. A filling machine of the character described in claim 11 wherein said last mentioned means includes means for applying a back pressure to the lubricating

liquid in said pair of grooves and means for stopping said rotary turret structure when pressure of said lubricating liquid in said pair of grooves drops below a predetermined value.

5 13. A filling machine of the character described in claim 10 including an annular member carried by said table outwardly of said rings on said table, said member being U-shaped in cross section, said ring on said rotary turret structure having a pair of annular concentric grooves therein on its downwardly facing surface for receiving the ends of said member to provide a water trap.

10 14. A filling machine of the character described in claim 13 wherein said ring on said stationary frame structure is provided with radially extending slots in its bottom surface whereby lubricating liquid passing over sides of the rings from between the bearing surfaces thereof can be returned inwardly of the ring onto the table of said stationary structure.

15 15. A filling machine of the character described in claim 10 wherein said ring on said stationary frame structure is provided with radially extending slots in its bottom surface, and wherein said slots are in communication with said lubricating liquid return grooves whereby liquid can be returned inwardly of the ring onto the table of the stationary structure.

20 16. In a filling machine for filling containers: a stationary frame structure having an upwardly facing horizontal annular bearing surface, said surface being provided with a pair of concentrically spaced lubricating liquid grooves and a first arcuate gaseous fluid pressure groove concentric with and intermediate of said pair of liquid grooves and a second arcuate gaseous fluid groove also concentric with and intermediate of said pair of liquid grooves; a rotary turret structure comprising a

25 plurality of cylinders, a container supporting platform cooperating with each of said plurality of said cylinders and adapted to be moved vertically by fluid pressure in said cylinders from a lower position to an upper position, a plurality of filling heads one being in vertical alignment with each container supporting platform and a reservoir, said rotary turret having a downwardly facing horizontal annular bearing surface cooperating with said upwardly facing bearing surface of said stationary frame structure; means for applying a liquid under pressure

30 from a source of lubricating liquid to said pair of liquid grooves whereby said rotary turret structure is supported for rotation on said stationary frame structure by a film of liquid, means to return said lubricating liquid to said source from between said bearing surfaces; means for supplying a gaseous fluid under pressure to said first

35 mentioned arcuate groove; means connecting said second arcuate groove to atmosphere; and individual fluid connecting means between each of said cylinders and the bearing surface of said rotary turret structure, said last mentioned means cooperating with said first and second arcuate grooves whereby said container supporting platforms are raised vertically when gaseous fluid under pressure is supplied to the cylinders through said fluid connecting means and said first actuate groove and wherein fluid pressure in said cylinders is exhausted through said fluid connecting means and said second actuate groove so said container supporting platforms can be lowered.

40 17. In a rotary filling machine for filling containers: a stationary frame structure having an upwardly facing annular bearing surface; a rotary turret structure comprising a downwardly facing annular bearing surface

45 complementary in size and cooperating with said upwardly facing bearing surface, a plurality of container supporting platforms, a plurality of filling heads in vertical alignment with said platforms, and a reservoir; one of said first and second mentioned bearing surfaces having at least two concentric annular grooves extending substantially around the same, means to supply a lubricating liquid from a source of lubricating liquid to said

50 grooves at a predetermined pressure whereby a film of

15

lubricating liquid is formed between said bearing surfaces sufficient to support the rotary turret on said stationary frame for rotation; means to return said lubricating liquid to said source from between said surfaces, means to supply a gaseous fluid at a predetermined pressure to said container supporting platforms to operate the same, said last-mentioned means including a distributor manifold groove in one of said bearing surfaces intermediate said lubricating liquid grooves whereby said lubricating liquid between said bearing surfaces provides a seal for the gaseous fluid.

18. In a rotary filling machine for filling containers: a stationary frame structure having an upwardly facing annular bearing surface; a rotary turret structure comprising a downwardly facing annular bearing surface complementary in size and cooperating with said upwardly facing bearing surface, a plurality of container supporting platforms, a plurality of filling heads in a vertical alignment with said platforms and a reservoir; said up-

16

wardly facing bearing surface having at least two pairs of concentric annular grooves therein; a source of lubricating liquid; means for supplying lubricating liquid from said source to each groove of each pair of grooves at a predetermined pressure whereby said turret structure is supported for rotation on said frame structure by a film of lubricating liquid; means including one groove intermediate the grooves of each pair of grooves for returning lubricating liquid to said source; and means to supply a gaseous fluid under pressure to said container supporting platforms to operate the same, said means including a distributor manifold groove in said upwardly facing bearing surface intermediate said first and second pairs of lubricating liquid grooves.
